[57] CLAIM

The ornamental design for a dental flosser, as shown and described.

DESCRIPTION

FIG. 1 is a top perspective view of a dental flosser showing my new design;

FIG. 2 is a left side elevational view thereof, the right side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is an exploded perspective view thereof, the floss compartment shown broken away for convenience of illustration.

FIG 2

FIG 4

FIG 3

FIG 1
